CLAIM

The ornamental design for a socket tool, as shown and described.

DESCRIPTION

FIG. 1 is a front and bottom plan view of a socket tool.
FIG. 2 is a left side plan view of a socket tool.
FIG. 3 is a left and bottom left side plan view of a socket tool.
FIG. 4 is a top plan view of a socket tool.
FIG. 5 is a bottom plan view of a socket tool; and,
FIG. 6 is a right and bottom side plan view of a socket tool.
The broken line showing of a socket tool is included for the purpose of illustrating portions of the article and forms no part of the claimed design.

1 Claim, 6 Drawing Sheets
